WEDGE ATTACHMENT FOR HYDRAULIC FEEDING MECHANISM

Otto J. Bratz, Adrian, Mich., assignor to American Chain & Cable Company, Inc., Bridgeport, Conn., a corporation of New York

Application February 24, 1944, Serial No. 523,757

6 Claims. (Cl. 78—98)

1

This invention relates to improvements in metal working machines.

Among the objects of this invention are improvements in means for controlling the size of the opening in swaging dies and for decreasing the size of the opening during the swaging operation and for controlling the extent of the decrease in the size of the opening.

Another and more specific object of this invention consists in providing a fluid operated means for adjusting the position of a lower die in a press swaging machine and for moving the die upwardly during the swaging operation and for controlling the amount of such upward movement with respect to the amount of feeding movement given to the element to be worked on said die.

Another object consists in combining such die controlling mechanism with other mechanisms of a press swaging machine and for adjusting the position of the lower die by means operated by the fluid which rotates the work and feeds the work into the dies.

Other objects of this invention will appear from the following description taken in connection with the drawings, in which:

Fig. 1 is a front elevational view of a standard press swaging machine showing attachments embodying the principles of this invention;

Fig. 2 is a vertical section through the lower die adjusting means taken on the line 2—2 of Fig. 1;

Fig. 3 is a top plan view of the lower die adjusting means;

Fig. 4 is a vertical section on the line 4—4 of Fig. 5, showing a valve mechanism for controlling the pressure of the fluid against the feeding piston;

Fig. 5 is a vertical section through the fluid pressure supply pump mechanism; and

Fig. 6 shows dies that may be employed in swaging spherical end fittings.

The invention is disclosed in connection with a standard vertical press type swaging machine disclosed in my application Serial No. 475,450, filed February 10, 1943, now Patent No. 2,347,875, granted May 2, 1944, which includes a frame, Fig. 1, provided with a base 15 on which are supported standards 16 and 17 in which is journaled a press operating crank shaft 18. Supported on the standards is an oil reservoir 19, Figs. 1 and 5, which supports a pump mechanism 20 and a valve control mechanism 21, Figs. 1 and 4. Also supported and secured on the base 15, Fig. 1, by bolts 23 and projecting to the right thereof is a platform 24 on which is supported an adjustable

2

swaging die 25 and the mechanism for feeding and rotating the article to be swaged.

The movable swaging die indicated at 26, Fig. 1, is supported as usual on a vertically reciprocable ram 27 suitably guided in the standards for operation by the crank shaft 18. The shaft 18 may be driven by a motor not disclosed through a belt 28, as indicated. Braking means indicated at 29 and 30 is provided for releasing and stopping the machine and this may be operated from a foot pedal (not disclosed) through linkage connections 31 and 32 from a shaft 33 (see also Fig. 4).

Supported on the right-hand end of the platform 24, Fig. 1, is a fluid cylinder 35 in which reciprocates and rotates a hollow piston 36 connected to a sliding rod 38, on the end of which is threaded a fitting holder 39 provided with a recess to receive the head of a fitting 40 and with a transverse pin 41 to hold the fitting in the recess. A cable 42 on which the fitting is to be swaged is shown in dot and dash lines.

The left-hand end of the sliding rod 38 is slidably supported in a stop block 46 which may be made adjustable and held in adjusted position on the platform 24, as disclosed in said application, by means of threaded bolts 47 passing through slots in flanges on the block and threadedly engaging any one of a series of holes in the platform 24. This block is provided for the purpose of adjusting the home position of the fitting holder and also the most forward position of the fitting holder.

The forward end of the sliding rod 38 is provided with a stop member 51 threaded thereon for engagement with the left-hand end of the block 46 to stop the sliding rod in its home or rearward position. Mounted on the sliding rod for cooperation with the right-hand end of the block 46 is an adjustable stop member 52 which may be secured in adjusted position on the sliding rod to limit the forward feeding movement of the sliding rod 38 and the fitting holder 39. By adjusting the stop block 46 and the stop member 52 the forward and rearward limits of movement of the sliding rod and fitting holder may be fixed. In setting the block 46 for a series of operations on fittings of the same size the block is so adjusted that the small end of the fitting, that is, the end of the fitting into which the cable is inserted, will extend half way into the bell mouth of the dies. This has the advantage that the first one or two swaging operations on the fitting will reduce the fitting less than

if the end of the fitting were extended into the cylindrical portions of the dies.

As disclosed in Fig. 1, a weight 55 may be provided for returning the sliding rod 38 to the right into its home position as determined by the position of the block 46. For this purpose there is provided a sleeve 56 which is rotatably supported in the sliding rod and is mounted for movement with the sliding movement of the sliding rod 38 and to which the weight 55 is connected by means of a cable 57 passing over a pulley 58. The sleeve 56 is moved forwardly by the piston 36 by means of a sleeve 60 movable with the sliding rod 38.

For the purpose of rotating the sliding rod 38 there is provided a rotary pump construction including a housing 62, Fig. 1, which is secured to an end of the cylinder 35 and constitutes the closed end or head of the cylinder. Inside of the housing 62 is a rotor 63 of any suitable construction to be rotated by fluid under pressure forced into the housing through a pipe 67. Supported in the end walls of the housing 62 is a shaft 68 to which the rotor is keyed. This shaft extends into the cylinder 35 and is provided with a non-circular end 69 non-rotatably and slidably extending through a hole in the outer end wall 70 of the hollow piston 36. By means of this construction the piston may slide with respect to the shaft 68 as the rotor communicates rotational movement to the piston and to the sliding rod 38.

As disclosed in Fig. 1, the fluid under pressure will leave the rotor through a port 71 extending through one wall of the rotor casing and intersecting a radial port 72 in the cylinder 35 through which the fluid passes into the cylinder to move the piston 36 and sliding rod 38 forwardly at the same time that these parts are rotated by the rotor.

Connected to the outer end of the port 72 is a pipe 73 through which the fluid under pressure is permitted to escape after the arrest of the forward movement of the piston and rod 38 which permits the piston and rod to be rotated after their forward movement has been arrested. The pipe 73 directs the fluid to a valve mechanism for conditioning the piston for operation and for controlling the amount of forward movement of the piston on each stroke of the fluid supplying mechanism and to means for operating and for controlling the position of the lower die 25.

For purposes of supplying fluid under pressure there is provided, Fig. 5, a pump mechanism 20 which as disclosed may be supported on the fluid reservoir 19. Projecting upwardly from the bottom of the reservoir 19 is a hollow cylindrical guiding member 74. The pump cylinder block of the pump mechanism 20 is provided with a cylindrical opening 75 in communication with a port 76 in a detachable valve block 77, which port 76 is in communication with the fluid in the reservoir 19 through an intake valve 78, and with the pipe 67 leading to the rotor through an outlet valve 79 and with the reservoir through an adjustable safety relief valve 80. This latter valve is made adjustable so that no damage will be done to the pump mechanism or the rotor by excessively high pressures that might otherwise be developed by the pump.

Threaded in the lower end of the cylindrical opening 75 in the pump block is a long sleeve 81 which constitutes in effect the body of the pump cylinder and in which operates a pump piston 82 against a return spring 83 between the piston and the end wall of the cylinder. One side of

the outer end of the piston 82 is cut away to provide a shoulder 84 to engage a stop 85 on a vertically adjustable slide 86 mounted on the outer face of the pump block and made adjustable by means of a threaded nut 87. By means of this adjustment the downward movement of the piston may be limited to control the amount of fluid delivered by the pump on each working stroke which in turn controls the amount of angular rotation and forward movement given to the sliding rod 38, Fig. 1, and to the fitting 40.

The piston is operated on its upward stroke by the upward movement of the ram 27, Fig. 1, which reciprocates the die 26. As disclosed in Figs. 1 and 5, the cap of the ram 27 is provided with a block 90 which engages a roller 91 supported on a rod 92 slidable within the cylinder 74. The upper end of the rod is provided with a head 93 adapted to engage and operate the pump piston 82. The roller 91 is held in contact with the block 90 by means of a spring 97 connected between the head 93 and the bottom wall of the reservoir 19. By means of this construction the pump is operated during every operation of the movable die after it has disengaged the work and as it is being raised, so that in all cases the work or fitting is free to be rotated and moved forward as the pump is operated.

At the beginning of a swaging operation no fluid must be permitted to flow through the return pipe 73, Figs. 1 and 5, in order that the fluid which rotates the rotor and the sliding rod 38 may also move the sliding rod 38, Fig. 1, forwardly to feed the fitting into the dies. When the forward movement of the sliding rod 38 and fitting has been stopped the fluid entering the pump must be discharged through the pipe 73 in order that the sliding rod 38 and fitting may be rotated to apply several additional swaging operations on the fitting.

Also supported on the reservoir 19 is the valve mechanism 21, Figs. 1, 4 and 5, which comprises a sliding valve 100 spring pressed by a spring 101 bearing on an adjustable member 102 which may be turned by a manipulative means 103 to adjust the compression of the spring 101 and therefore the pressure required to move the valve 100 into an open position, Fig. 4, permitting the fluid in the pipe 73 to by-pass the valve and to pass into the reservoir 19. This valve may be adjusted to control the pressure of the fluid on the piston 36 and therefore to control the amount of forward feed for a given amount of fluid discharged into the cylinder 35. By this means the amount of forward feed of the fitting may be varied from zero to that produced by a capacity delivery from the pump and for any amount of fluid delivered by the pump.

The body of the valve 100 is slotted as shown at 104, and into the space between the end wall 105 of the slot and a pin 107 which extends through the walls of the slot projects the short arm of a bell crank 106. The long arm of the bell crank is connected by means of a cable 108 passing over a pulley 109 with an arm 110 on a block 111 clamped to the brake operating shaft 33. As the brakes are applied to stop the machine, the bell crank 106 is rocked counter-clockwise into the position shown in Fig. 4, opening the valve 100 which permits the weight 55 to return the sliding rod 38 to its home position. When the brakes are released the bell crank 106 is moved clockwise, which permits the valve 100 to seat and close the end of the pipe 73. As the press operates, the pumping mechanism will be

operated on each upward stroke of the upper die and the fitting to be swaged will be simultaneously rotated and moved forward. When the forward movement of the fitting is arrested by the stops 46 and 52, then the pressure of the fluid in the pipe 73 will open the valve 100 and discharge the fluid into the reservoir 19.

Prior to the swaging operation the machine is adjusted for the particular type of work to be swaged. The block 46 which controls the movement of the sliding rod 38 to the right is adjusted so that the small end of the fitting extends half way into the bell mouth of the dies. The stop 52 is then adjusted on the sliding rod 38 to control the length of the swaged portion of the fitting. The stroke of the pump 20 is adjusted to control the amount of fluid delivered to the rotor 63 to control the amount of rotation given to the fitting between successive strokes of the press. The fluid discharged from the rotor is discharged against the piston 36 and will move this piston forwardly and feed the fitting into the dies an amount in proportion to the amount of fluid delivered against the piston. The amount of movement of the piston may be controlled by adjusting the valve 100, Fig. 4, which controls the pressure of the fluid operating on the piston. This valve may be adjusted so that there will be no forward movement of the piston or so that there will be any amount of forward movement of the piston up to the amount of movement that would be produced if all of the fluid discharged by the rotor displaced the piston.

When the machine is at rest and the brakes are applied the valve 100, Fig. 4, will be in the position indicated. When the brakes are released the valve will be permitted to close, causing the fluid discharged from the rotor into the cylinder 35 to move the piston forwardly and feed the article to be swaged through the dies, in amounts dependent upon the compression of the valve spring 101 which controls the amount of fluid discharged through the pipe 73 past the valve 100. When the adjustable stop 52 engages the adjustable block 46, Fig. 1, the forward feeding movement of the sliding rod 38 and fitting 40 are arrested, the fluid discharged from the rotor discharging through the pipe 73 past the valve 100 into the oil reservoir. When the brakes are applied, the valve 100 is moved into the position shown in Fig. 4 permitting the free discharge of the fluid through the pipe 73 which permits the weight 55 to return the sliding rod 38 into its right-hand home position.

The improved lower die adjusting mechanism is disclosed in Figs. 2 and 3. The upper face of the bolster plate of the base 15, Figs. 1, 2 and 3, is provided with a transversely extending groove 120 located under the platform 24 in which is slidably mounted a wedge block 121 on which is seated a wedge member 122 supporting the lower die 25. The platform 24 is provided with an opening 127 into which extends a die holder 128 which is secured on the platform 24 as indicated. A cable guide block 129 is secured in a transverse groove 130 in the platform 24. The lower die 25 is provided with a flattened portion 132 against which bears the end of a screw threaded bolt 133 threaded through the wall of the die holder 128 to prevent rotation of the die 25 but to permit movement of the die 25 under control of the wedge block 121.

Bearing against one end of the wedge block are the ends of a pair of springs 135, Figs. 2 and 3, which urge the wedge block toward the left

in these figures against a rod 137 carried by a piston 138 operating in a cylinder 139 to which fluid is supplied from the return pipe 73 by a branch pipe 140.

5 The piston rod 137 is slidable in a sleeve 142 which is externally threaded for purposes of adjustment for controlling the extent of return movement of the wedge block 121. By means of this construction the home position of the wedge can be adjusted so as to control the position of the lower die 25 at the beginning of a swaging operation.

For the purpose of controlling and limiting the amount of forward movement of the wedge block 15 121 there is provided a rod 150 which is adjustably threaded in the bolster plate of the base 15 and which projects into the groove 120 and controls the forward position of the wedge block 121.

In swaging elongated sleeve-like fittings, the 20 machine can be operated in the same manner as the machine disclosed in the application referred to and, if desired, the adjusting wedge block can be held against movement and the position in which it can be so held can be varied to adjust the position of the lower die 25.

If it is desired to cause the lower die to be raised during a plurality of cycles of the machine, then the adjustable sleeve 142 and the adjustable rod 150 can be adjusted so as to not only determine the lowermost position of the lower die 25 but also to control the amount of movement of the lower die before it is arrested.

As the fluid discharged from the rotor and the 35 cylinder which rotate and feed the work operates the piston 138 which moves the wedge block that adjusts the lower die, it is obvious that the adjustment of the lower die can be continued after the forward feeding of the work has been stopped, and also in cases in which the adjusting block 40 52, Fig. 1, has been so adjusted as not to permit any forward movement of the work. This last adjustment would be availed of in the case of swaging spherical end fittings on to cables in which no feeding movement is desired but in 45 which it is desirable to rotate the work.

In swaging spherical fittings 40A to a cable 42A, spherical dies 26A and 25A are employed, as shown in Fig. 6. The cable 42A with a fitting 40A may be held in the position indicated and rotated 50 by hand or a suitable adapter 39A gripping the cable may be substituted for the adapter 39, Fig. 1. In this case the block 52 would be moved into the position shown in Fig. 1 to prevent any feeding movement of the work supporting rod 38 but the rod would be rotated during each cycle of operation as before.

While the invention has been described with particularity as to a preferred form of die controlling means in a particular type of machine 60 specifically described, it is to be understood that the right is reserved to all such changes in the die controlling means and in mechanisms used in combination therewith as fall within the principles of this invention and the scope of the appended claims.

I claim:

1. In a swaging machine the combination of a 70 slidably and rotatably mounted work support, relatively reciprocable swaging dies, a fluid operated piston for moving said work support to feed the work into said dies, a fluid operated rotor for rotating said work support to rotate the work within said dies, fluid operated means for controlling the opening between said dies, means for supplying fluid under pressure to said rotor, a

fluid conduit for carrying fluid discharged from said rotor to the working side of said piston, and a fluid conduit for carrying fluid from the working side of said piston to said fluid operated die controlling means.

2. In a swaging machine the combination of a slidably and rotatably mounted work support, relatively reciprocable swaging dies, fluid operated means for moving said work support to feed the work into said dies, fluid operated means for rotating said work support to rotate the work within said dies, fluid operated means for controlling the opening between said dies, means for supplying fluid under pressure to said rotating means, a fluid conduit for carrying fluid discharged from said rotating means to the working side of said feeding means, and a fluid conduit for carrying fluid discharged from the rotating means to said fluid operated die controlling means.

3. In a swaging machine the combination of a slidably and rotatably mounted work support, relatively reciprocable swaging dies, a fluid operated piston for moving said work support to feed the work into said dies, a fluid operated rotor for rotating said work support to rotate the work within said dies, fluid operated means for controlling the opening between said dies, a fluid supply tank, means for supplying fluid under pressure to said rotor, a fluid conduit for carrying fluid discharged from said rotor to the working side of said piston, a fluid conduit for carrying fluid from the working side of said piston to said fluid operated die controlling means, a fluid conduit connecting said last mentioned conduit to said tank and a valve controlling the pressure at which said fluid is discharged into said tank.

4. In a swaging machine the combination of a slidably and rotatably mounted work support, relatively reciprocable swaging dies, a fluid operated piston for moving said work support to feed the work into said dies, a fluid operated rotor for rotating said work support to rotate the work within said dies, wedge means for controlling the opening between said dies, a fluid operated piston for operating said wedge means, a fluid supply tank, means for supplying fluid under pressure to said rotor, a fluid conduit for carrying fluid discharged from said rotor to the working side of said first mentioned piston, a fluid conduit for carrying fluid from the working side of said first mentioned piston to the working side of said second mentioned piston, means for adjusting the initial position of said wedge means and

means for controlling the extent of forward movement of said wedge means.

5. In a swaging machine the combination of a slidably and rotatably mounted work support, relatively reciprocable swaging dies, a fluid operated piston for moving said work support to feed the work into said dies, a fluid operated rotor for rotating said work support to rotate the work within said dies, wedge means for controlling the opening between said dies, a fluid operated piston for operating said wedge means, means for supplying fluid under pressure to said rotor, a fluid conduit for carrying fluid discharged from said rotor to the working side of said first mentioned piston, a fluid conduit for carrying fluid from the working side of said first mentioned piston to said second mentioned piston, means for adjusting the initial position of said wedge means and means for controlling the extent of forward movement of said wedge means, said last mentioned means being adjustable to hold said wedge means against movement by said second mentioned fluid operated piston.

6. In a swaging machine, the combination of a slidably and rotatably mounted work support, relatively reciprocable swaging dies, means for moving said work support toward said dies and for rotating the same during each cycle of operation of the dies, means for controlling the increments of feeding movement and rotation during successive cycles of reciprocation of said dies, means for adjusting the size of the opening between the dies, adjustable means for arresting the feeding movement of the work support, means decreasing the size of the opening between the dies after said feeding means has been arrested, and adjustable means for predetermined the amount of decrease of the size of the opening effected by said decreasing means.
